UNITED STATES PATENT OFFICE.

HARRY W. HAMILTON, OF INDIANAPOLIS, INDIANA, ASSIGNOR TO THE HAM-MEIX MANUFACTURING COMPANY, OF INDIANAPOLIS, INDIANA, A CORPORATION OF INDIANA.

STARTER FOR INTERNAL-COMBUSTION ENGINES.

1,149,133.

Specification of Letters Patent.

Patented Aug. 3, 1915.

Application filed October 18, 1911. Serial No. 655,410.

To all whom it may concern:

Be it known that I, HARRY W. HAMILTON, a citizen of the United States, residing at Indianapolis, in the county of Marion and 5 State of Indiana, have invented a new and useful Starter for Internal-Combustion Engines, of which the following is a specification.

My invention relates to the starting of internal combustion engines.

In order to avoid the shock to the bearings occasioned by starting an internal combustion engine by an explosion within it while the engine is at rest, it has been proposed 15 to start the engine by the injection of air under pressure into the engine cylinders. This produces an easy starting; but is open to the objections that in order to obtain the air under pressure it is necessary 20 to use pumps or other moving parts, which easily get out of order, and that the flooding of the engine cylinders with air makes the explosions on several succeeding operations of the engine piston more difficult to obtain 25 on account of the resultant thinning of the explosive mixture.

It is the object of my present invention to obtain an easy starting of an internal combustion engine, without shock to the 30 bearings, and without the objections noted above.

In carrying out my invention, the engine is started by injecting into it a gas under pressure which is produced and maintained, 35 or rather replenished, to a substantially constant value as the gas is used, this gas being preferably a combustible gas obtained from a chemical gas generator. The most convenient gas for this purpose now known to 40 me is acetylene gas, which may be obtained cheaply at the necessary pressure by the action of water on calcium carbide in a suitable generator which preferably has some storage capacity.

45 The various novel features of my invention will appear from the description and drawings and will be particularly pointed out in the claims.

The single figure of the drawing illustrates 50 my invention semi-diagrammatically.

The engine 10, which is shown as a four-cylinder engine having the usual inlet and exhaust connections, may be of any desired type. In addition, each engine cylinder is 55 connected by a pipe 11 to a suitable distrib-

uter 12, which is driven, as by a chain 13 and sprocket wheels of proper size, from the engine shaft 14, and is timed in a manner identical with the usual timing of the ignition. In each pipe 11 is a suitable valve 8, 60 which is preferably located close to the engine cylinder. The valves 8 are preferably controlled in common by a single operating handle 9. The distributor is supplied, through a pipe 15 and a central valve 16, 65 from a chemical gas generator 17.

A convenient form of chemical gas generator is shown in the drawing. Here the generator comprises two compartments 18 and 19, separated by a gas-tight partition 70 20. The two compartments are for calcium carbide and water respectively, which may be introduced into their proper compartments through openings normally closed by screw plugs 21 and 22. There may also be a safety 75 valve 221. A pipe 23 leads from the bottom of the compartment 19 to the top of the compartment 18, the branched end of the pipe 23 in the compartment 18 being provided with a number of openings to distribute the water 80 over the carbide.

The plug 21, which is screwed into place after the two compartments 18 and 19 have both been properly charged and the plug 22 85 screwed in place, is provided with a cup 24 for the initial charge of water. This initial charge of water, which is discharged upon the calcium carbide after the cap 21 has been screwed in place and the generator turned to the position shown, reacts with the 90 calcium carbide to produce acetylene gas; which raises the pressure within the compartment 18 and forces its way through the pipe 23 into the compartment 19 until the gas pressure within the two compartments 95 is the same. This gas pressure is sufficiently high so that when it is supplied to the engine 10 it operates such engine by direct fluid pressure. The value of this gas pressure may be regulated by varying the 100 amount of water in the initial charge. As gas is used from the compartment 18, as through the pipe 15, the pressure within such compartment is diminished, whereupon the pressure above the water in the compartment 19 forces some water through the pipe 23 into the compartment 18, where it reacts with the calcium carbide to form more 105 gas and thus raise the pressure within the gas generator to its normal value. The 110

parts are so proportioned that this pressure is thus maintained substantially constant, or, perhaps more accurately, replenish to a substantially constant value.

In order to start the engine 10, the valves 8 and 16 are opened and gas is supplied from the gas generator 17 through the distributor 12 into the proper cylinder or cylinders of the engine 10, which cylinders are

- 10 those which are on their explosion strokes. The pressure of this injected gas starts the engine, which immediately after starting usually begins to operate by its own power, whereupon the valves 8 or 18, or both, are closed. The injected gas from the generator 17, by enriching the explosive mixture, may furnish part or all of the combustible gas for the early explosions following starting, depending upon the scavenging action of the engine and the initial efficiency of the carburetor used. Only a small amount of gas is used from the gas generator, one charging of which is generally sufficient for many hundreds, or even thousands, of startings.
- 25 The pressure produced by the gas generator 17 is maintained at, or replenished to, a substantially constant value for all of these startings.

My invention is not limited to the precise arrangement shown, but is capable of wide modification. I therefore aim to cover all modifications of my invention which do not involve a departure from its spirit and scope as set forth in the following claims.

35 What I claim as new is:

- 1. That improvement in the art of starting an internal combustion engine comprising freshly producing a warm gas under sufficient producer pressure to drive an engine forwardly, injecting the said freshly produced gas into the engine cylinder, and subsequently connecting the said engine with

a regular fuel supply and the ignition means.

2. That improvement in the art of starting an internal combustion engine comprising freshly producing a warm combustible gas under sufficient producer pressure to drive an engine forwardly, injecting the said freshly produced gas into the engine cylinder, and subsequently connecting the said engine with a regular fuel supply and the ignition means.

3. The combination with an internal combustion engine provided with usual fuel supply and igniting means, of an automatic gas generator associated with the engine and provided with means for controlling gas generation to replenish the gas pressure to a substantially constant value, by which a freshly generated warm gas may be injected into the engine cylinder under sufficient pressure without ignition to start the engine forwardly.

4. The combination with an internal combustion engine provided with usual fuel supply and igniting means, of an automatic gas generator associated with the engine and provided with means for controlling gas generation to replenish the gas pressure to a substantially constant value, by which a freshly generated warm combustible gas may be injected into the engine cylinder under sufficient pressure without ignition to start the engine forwardly.

In witness whereof, I have hereunto set my hand and seal at Indianapolis, Indiana, this sixteenth day of October, A. D. one thousand nine hundred and eleven.

HARRY W. HAMILTON. [L.S.]
